UNITED STATES PATENT OFFICE.

GEORGE M. BAKER, OF BROOKLYN, NEW YORK.

PUMP.

1,356,589.

Specification of Letters Patent. Patented Oct. 26, 1920.

Application filed September 12, 1917. Serial No. 190,944.

To all whom it may concern:

Be it known that I, GEORGE M. BAKER, residing at Brooklyn, in the county of Kings and State of New York, have invented certain new and useful Improvements in Pumps, of which the following is a specification.

This invention relates to improvements in pumps, and more particularly to pumps of the rotary type.

One of the objects of the invention is to provide a pump of the above type of simple construction which will operate more efficiently than pumps of this type as hitherto constructed.

Another object of the invention is to provide a pump which can be manufactured at a modicum of cost, which will occupy a minimum amount of space, is extremely light in weight when considering its capacity, the construction being such that there is a complete cut-off of the intake and outflow upon every revolution of the rotary pumping means.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claim.

In the accompanying drawings wherein I have illustrated a preferred form of embodiment of my invention:

Figure 1 is a sectional view looking endwise of the pump, with one of the end heads of the casing removed so as to disclose the interior mechanism.

Fig. 2 is a similar view, partly in section, showing the parts in a different position.

Fig. 3 is a vertical sectional view taken on line III—III of Fig. 2.

Fig. 4 is a view in elevation, partly in section, showing the guide means for the pumping member.

Fig. 5 is a plan view of a detail of said guide means; and

Fig. 6 is an elevational view of the means employed to actuate the pumping member.

Referring now to the drawings wherein similar reference characters are used to designate similar parts, the reference numeral 1 denotes the base of a casing com-

prising the end walls or heads 2 and 3 respectively, between which is positioned a substantially U-shaped section 4 of the casing and a cylindrically formed casing member 5, the latter being securely bolted as at 60 6 and 7 to the upper ends of the U-shaped casing member 4, which are shaped to conform to the contour of the cylindrical member 5. The parts just described are securely fastened together by means of bolts which 65 pass through the marginal portions of the end heads 2 and 3, and flanges 8 and 9 formed upon the cylinder 5, and the U-shaped casing member 4, suitable packing 70 of course being provided to insure moisture tight joints.

Located within the cylinder 5, and extending longitudinally thereof, is the pumping member, the same comprising a cylindrically formed hollow member 10, having 75 a diameter smaller than the interior diameter of the casing 5, and the ends of the pumping member are in close sliding engagement with the inner walls of the end casing members 2 and 3. The pumping member 80 10 has a downwardly extending baffle member 11 which projects through an opening formed in the lowermost portion of the cylindrically formed part of the casing 5, and divides the latter into an intake 85 opening 12 and an outflow opening 13, it being understood that the baffle member 11 is coextensive in length with the pumping member 10 and closely engages the inner surfaces of the end heads 2 and 3.

Located interiorly of the lower casing member 4, and resting on the inner surface of the bottom wall thereof, is a bracket 14 having upwardly extending walls 15 and 16, which extend longitudinally of the casing, and are in tight engagement with the end heads 2 and 3 of the casing. Resting upon the upper ends of the walls 15 and 16 is a tubular member 17, the outer ends of which extend through apertures 18 and 19 100 formed in the end heads 2 and 3 respectively of the casing. This tubular member is provided with an elongated slot 20 and is held in the position shown in Fig. 3 of the drawings, as by means of cap pieces 21 and 105 22, which have threaded engagement with the ends thereof and hold it in a position so that the ends 23 and 24 of the slot lie in the same plane as do the inner walls of the end members 2 and 3 of the casing. In 110

other words, the slot 20 is coextensive in length with the width of the interior diameter of the casing which incloses the pumping apparatus.

- 5 Located within the tubular member 17 is another tubular member 25, which has an elongated slot 26 which extends entirely therethrough, said slot 26 when the parts are in position being coextensive in length 10 with the slot 20 and the member 17, but being of a less width for a purpose which will be presently understood. The tubular member 25 is closely fitted within the tubular member 17, so that a water tight joint 15 is provided which will nevertheless permit the tubular member 25 to rotate within its supporting part. The baffle member 11 extends downwardly through the slot 26 and 20 into a chamber 27 formed in the bracket member 14, thus providing room for the lower end of said baffle member to oscillate during the operation of the pump, which will be hereinafter described.
- 25 It will thus be seen that the partitions 15, 16, and the construction of the guide members 17 and 25, together with the baffle 11, divides the lower part of the casing 4 into two compartments 28 and 29 respectively, 30 one of which accommodates the intake of the pump, and the other of the outflow thereof; the intake, being supplied as by means of a conduit 30 leading into the compartment 28, and the outflow being accommodated as by means of a conduit 31, which 35 extends from the compartment 29.
- 35 The reference numeral 32 denotes the drive shaft of the pump, which extends through the heads 2 and 3, and is provided with suitable bearings 33 and 34, suitable 40 driving means being provided for this shaft as by means of the pulley and belt indicated at 35.
- 45 Keyed upon the shaft 32 interiorly of the casing are arms 36 and 37 respectively, 50 said arms being disposed in spaced relation upon the shaft, and having their outer ends formed arc-shaped, as shown in Figs. 1 and 2 of the drawings, and extending into circumferentially formed recesses 38 and 39 55 provided in a roller 40 which extends longitudinally of the cylindrically formed pumping member 10 and within the same. The outer arc-shaped ends of the arms 36 and 37 engage with the bottom wall of the 60 recesses 38 and 39 in the roller 40, and the lengths of said arms are such that the roller 40 engages with the cylindrically formed pumping member 10 and holds it in close 65 engagement with the inner surface of the cylinder 5, so that when the shaft 32 is rotated the pumping member 10 will be oscillated within the cylinder 5, the opposing walls being at all times in close engagement; it being understood that the inner 70 65 surface of the cylinder 5, and the outer sur-

face of the cylinder 10 are ground so that a close liquid tight engagement is formed between these two parts.

70 The baffle member 11 which extends through the guide slot 26 with the member 25, prevents the pumping member 10 from rotating, but permits it to partake of an oscillatory movement within the cylinder 5, during the operation of the pump.

75 Having thus described the construction of this embodiment of my invention, the operation thereof may now be understood.

80 Assuming the parts to be in the position shown in Fig. 1 of the drawings, it will be seen that the pumping member 10 has effected a complete cut-off of the intake and outflow apertures 12 and 13, and that a neutral condition has been established in the upper portion of the casing 5, which for 85 purposes of this specification it is assumed is filled with liquid to be pumped.

85 With the pump in operation and the drive shaft 32 rotating in the direction indicated by the arrow in Fig. 1, the engagement of the roller 40 with the inner wall of the 90 pumping member 10 will move the same to the left and upwardly, thereby forming a vacuum upon the intake side of the pump, at the same time opening the intake 12 and outflow 13, whereby the atmospheric pressure 95 will force the liquid into the intake side of the pump, and the liquid already in the pump will be forced through the outflow aperture 13, and be delivered from the pump to the chamber 29 and outflow conduit 31.

100 In Fig. 2 of the drawings the parts are shown in the position opposite to that in Fig. 1, the arrows indicating the manner in which the liquid is forced through the intake side of the pump and expelled through the 105 outflow side thereof. It will be seen that when the parts move to the position of Fig. 2 from the position shown in Fig. 1, all the liquid which has been contained within the 110 chamber of the pump will have been expelled during the complete revolution above described, and that a complete cut-off will again be established for the intake and outflow openings 12 and 13.

110 It will accordingly be seen that I have provided a construction well adapted to attain, among others, all the aims and objects pointed out, in an exceedingly simple and efficient manner, the pump being constructed of very few parts and no likelihood of the 115 same becoming disorganized. The fact that there is a loose driving engagement between the roller 40 and the pumping member 10, the roller 40, aside from oscillating the member 10, has also a tendency of wedging the 120 member 10 into close engagement with the inner surface of the cylinder 5, thereby increasing the efficiency of the vacuum produced during the pumping operation.

125 As many changes could be made in this 130

construction without departing from the scope of the following claims, it is intended that all matter contained in the above description or shown in the accompanying drawings shall be interpreted as illustrative only and not in a limiting sense.

Having thus described my invention what I claim as new and desire to secure by Letters Patent is:

- 10 A rotary pump, including an intake and outtake equipped casing having communicating compartmental chambers, one of said chambers having a hollow cylindrical pumping member arranged therein, said latter member being of less diameter than said chamber and having a downwardly extending baffle, said casing having an opening receiving said baffle and divided into an inlet and an outlet passage thereby, the other 15 compartmental chamber having a bracket with upwardly extending walls, a tubular member with closure covered ends projecting through said casing and having an elongated slot co-extensive with the interior of 20 the chamber containing the cylindrical 25

pumping member, said tubular member being superposed upon the upper ends of said bracket-walls, a second tubular member arranged within the aforesaid tubular member and having a slot extending entirely therethrough and co-extensive in length with the slot of the aforesaid tubular member but of less width than said slot, said baffle-member extending downwardly through the slot of said second tubular member, and into a 30 chamber of said bracket to provide for the oscillation of said baffle-member during the pump-operation, said bracket walls subdividing the lower compartmental chambers into additional sub-chambers, in communication with the intake and outtake of the casing and a driving shaft for and co-operating with said pumping member.

In testimony whereof I affix my signature in the presence of two witnesses.

GEORGE M. BAKER.
